ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

AXMINSTER LOOM

Application filed June 12, 1930. Serial No. 460,755.

This invention relates to Axminster looms of the type in which a large number of tube frames are provided, in order to produce a desired pattern in the woven fabric, such as a carpet or rug.

It is the general object of my invention to provide improved means for storing the tube frames and for presenting them successively in operative position. I also effect a substantial saving in storage space, and I transport the tube frames without inversion at any time.

A further object of my invention is to provide a construction having all of the advantages above set forth and in which the direction of feed of the pattern chain may be reversed.

My invention further relates to arrangements and combinations of parts which will be hereinafter described and more particularly pointed out in the appended claims.

A preferred form of the invention is shown in the drawings, in which

Fig. 1 is a side elevation of a portion of an Axminster loom embodying my improvements;

Fig. 2 is an enlarged side elevation of certain chain feeding mechanism;

Fig. 3 is an end elevation of certain parts, partly in section, and looking in the direction of the arrow 3 in Fig. 2;

Fig. 4 is a view similar to Fig. 3 but showing the parts in a different position;

Fig. 5 is an enlarged side elevation of a portion of the rack bars and the supporting devices therefor;

Fig. 6 is a sectional end elevation, taken along the line 6-6 in Fig. 5;

Fig. 7 is an enlarged side elevation of mechanism for feeding the rack bars;

Figs. 8 to 12 inclusive are diagrammatic side elevations, illustrating the cycle of movements of the rack bars;

Fig. 13 is a detail sectional plan view, taken along the line 13-13 in Fig. 5;

Fig. 14 is an enlarged end elevation of certain parts, looking in the direction of the arrow 14 in Fig. 1;

Figs. 15 and 16 are detail side elevations, looking in the direction of the arrows 15 and 16 in Fig. 14; and

Figs. 17, 18 and 19 are diagrammatic side elevations of certain operating cams to be described.

Referring to the drawings, I have shown a portion of the frame 20 of an Axminster loom, together with the usual carrier bars 21 and rocking arms 22, by which the tube frames T are presented at the fell of the pile fabric F.

The tube frames T are provided with gudgeons 24 adapted to be received in openings 25 in slotted links 26 which alternate with connecting links 27 in the carrier chains C.

The carrier chains C are mounted on upper sprockets 28 (Fig. 1) and lower sprockets 29 (Fig. 2). Additional carrier chains C' are shown at the right in Fig. 1 and are mounted on upper sprockets 30 and lower sprockets 31. The upper sprockets 28 and 30 rotate freely in bearings on an upper supporting frame 33 and the lower sprocket 31 is mounted in a bearing 34 at the rear or right hand end of a lower frame member 35.

The lower sprocket 29 is mounted on a cross shaft 37, rotatable in bearings in frame members 38 projecting forward from the upper part of the loom frame 20. The lower sprockets 29 and 31 are intermittently advanced by feeding mechanism to be described.

Tube frame holders 40 (Figs. 3 and 4) are pivotally mounted on the ends of the carrier bars 21 and are provided with studs 41 pivotally connected to the rocking arms 22. The holders 40 are provided with flanges 43 and 44 engaging the bottom and sides of the tube frame T.

Guards 45 close the openings 25 in the chains C and C' during the greater part of their travel and prevent the gudgeons of the tube frames from escaping from the slotted links.

An opening 46 is made in the guard for each chain C directly over the operative position of the tube frame holder, and a sliding block or support 47 on the holder enters the opening 46 as the holder is raised and provides a support for the outer end of the gudgeon 24 as the tube frame is advanced to a position over the opening 46.

The holders 40 are then moved inward by

the usual operating mechanism from the position shown in Fig. 3 to that shown in Fig. 4, and the block 47 slides outward on the holder against the pressure of a coil spring 5 48.

After the tube frame is firmly seated in the holders 40, the holders are lowered and rocked by suitable movements of the carrier bars 21 and rocking arms 22, such movements being 10 produced in the usual manner and forming no part of my present invention.

Feeding mechanism

15 Studs 50 (Fig. 2) are mounted on the sprocket 29 in position for engagement by feed pawls 51 or 52. Springs 53 are provided for the pawls 51 and 52, which springs are secured at points rearward of the axes of the pawls, so that they extend across the 20 axis and at one side or the other thereof, and are effective to hold the pawls yieldingly in the operative position of the pawl 51 (Fig. 2) or in the inoperative position of the pawl 52.

25 It will be understood that only one of these pawls is operative at a given time. When the pawl 51 is operative, the chain C is advanced in the direction of the arrow *a* in Fig. 2, and when the pawl 52 is operative, the feed will be in the opposite direction.

30 The pawls 51 and 52 are mounted on arms 54 and 55 swinging about the axis of the shaft 37 and regularly oscillated by connecting rods or links 56 and 57.

35 The feeding mechanism for the sprocket 31 is the same as the mechanism above described for the sprocket 29 and is actuated by links 58 and 59 (Fig. 1).

40 The links 56 to 59 are connected to a bell crank 60, pivoted at 61 and connected by a link 45 to a cam lever 63 having a roll 64 engaged by a feed cam 65 mounted on a continuously rotated cam shaft 66, which cam shaft also controls the movements of the tube frame carrier bars 21 and rocking arms 22. The lay 45 out of the cam 65 is shown diagrammatically in Fig. 19.

45 In order to permit removal or replacement of tube frames, I provide a removable section 70 in the guard 45, as shown in Figs. 14 to 70 16. The removable section 70 has a hub portion 71 pivoted at 72 to the upper end of the adjacent portion of the guard 45.

55 When the removable portion 70 is swung outward, a shoulder 73 on the offset portion 71 engages the guard 45 and supports the portion 70 in substantially horizontal position, as indicated in dotted lines in Fig. 16. In this position, the portion 70 forms a convenient support for tube frames which are to 60 be removed or inserted.

5 A latch 75 is pivoted at 76 above the removable portion 70 and may be swung upward to the dotted line position in Fig. 14 to release the upper end of the portion 70 and permit said portion to swing outward and

downward. An extra guard rail 77 (Fig. 1) is provided at the inside of the chain C in its forward vertical run, as indicated in Fig. 1.

The tube frames T are supported entirely on their gudgeons 24 during the transportation thereof and the weight is so distributed that the tube frames always remain in the vertical position indicated in Figs. 2 and 3.

Storage device

75 As the tube frames are of substantial height, this vertical positioning necessitates the spacing of the tube frames a substantial distance apart on the chains C and would require very long chains to transport an entire 80 series of tube frames in the usual manner, in which case all of the tube frames remain attached to the chains at all times, even while inoperative or in storage.

In order to prevent the need for chains of 85 excessive length, I have provided means for removing the tube frames from the chains and for storing them in closely adjacent horizontal rows while inoperative and I will now 90 describe my improved storage device and the mechanism for removing the tube frames from the chains and for restoring them to the chains for further use.

95 For storage purposes, I provide a series of fixed rack bars 80 (Figs. 5 and 6) and a series of movable rack bars 81. The fixed rack bars 80 are provided with shallow notches 82 to receive the gudgeons 24 when the tube frames T are at rest and to prevent accidental displacement thereof. The rack bars at 100 one end only of the tube frames are shown in the drawings but will it be understood that a similar series of parts is provided at the other end also.

The movable rack bars 81 are provided with 105 relatively deep notches 83 to receive the gudgeons 24 of the tube frames T during the advance or feeding movement thereof.

Bar raising mechanism

110 The movable rack bars 81 are slidably supported adjacent the fixed rack bars 80 by brackets 85 (Fig. 5) bolted to the lower portions of the fixed rack bars 80. The movable rack bars 81 are vertically supported upon 115 rolls 87 pivoted at 88 on supporting arms 89, which in turn are pivoted to fixed brackets 90.

A plurality of the supporting rolls 87 and 120 arms 89 are provided at different points in the length of the rack bars 81. The arms 89 are extended upward and are pivotally connected at 92 to an actuating bar 93. As the bar 93 is reciprocated, the rolls 87 will move from the full line to the dotted line position indicated in Fig. 5 and the movable rack bars 81 will be raised and lowered, also as indicated in full and dotted lines in Fig. 5.

125 The actuating bars 93 (Figs. 1 and 7) have a pin and slot connection (as indicated at 94 in Fig. 7) to an upright bar 95, which is 130

pivotedly supported on the upwardly extending arms of bell cranks 96 (Fig. 1). The bell cranks 96 are pivoted to an actuating rod 97 which is connected at 98 to a cam lever 99.

5 The lever 99 is provided with a stud or roll 100 (Fig. 7) positioned in a cam groove 101 formed in the side of a cam mounted on a cam shaft 102. As the cam is rotated, all 10 of the bars 93 are simultaneously reciprocated, raising and lowering the movable rack bars 81.

15 The effective action of the cam groove 101 is indicated diagrammatically in Fig. 17 and shows that the supporting rolls 87 are held in raised position for a quarter of a revolution and in lowered position for a quarter of a revolution and that they are raised or lowered during the intervening quarters.

Actuating mechanism

20 I will now describe the mechanism which reciprocates the rack bars 81 to advance or feed the tube frames. For this purpose, the rack bars are provided with studs 105 (Fig. 7) extending into slots 106 in the upwardly projecting arms of bell cranks 107 and 107^a.

25 The bell cranks 107 are pivoted at 108 on a supporting frame member and their horizontally extending arms are pivoted in spaced relation to a vertically movable bar 110, pivoted at its lower end to a cam lever 111 (Fig. 7). The bell cranks 107^a are similarly pivoted at 108^a and are pivotally connected to the vertical bar 110. The pivots 108 and 108^a are on 35 opposite sides of the bar 110 so that both cranks 107 and 107^a are simultaneously rocked in opposite directions. Alternate rack bars 81 are connected to bell cranks 107 and 107^a respectively.

40 The lever 111 is provided with a stud or roll 112 positioned in a cam groove formed in the side of a cam 113 mounted on the shaft 102 previously described. The effective actions of the cam is indicated diagrammatically in 45 Fig. 18, showing that the cam has three concentric operative portions 114, 115 and 116, thus effecting a dwell in the operation of the movable rack bars 81 at the extreme right and left positions and also at an intermediate position.

50 The fixed and movable rack bars 80 and 81 are arranged in superposed series, as clearly shown in Fig. 1. It is necessary that an even number of bars be used so that the tube frames may be removed from and return to the conveyor chains C, but any desired number of pairs of rack bars may be employed.

55 Short sectional guide-bars 120 (Figs. 5 and 13) are arranged at the ends of the rack bars and the adjacent ends of the sections 120 are spaced apart, as indicated in Fig. 5 to provide an opening 121 through which tube frames may be removed from the chains C or returned to the chains.

Reversible driving mechanism

The upper cam shaft 102 (Fig. 1) is connected by bevel gears to an upright shaft 122, which in turn is connected by sliding bevel gears 123 and 124 to a bevel gear 125 on the lower cam shaft 66. The upper and lower cam shafts are thus rotated in definite timed relation and the direction of rotation of the upper cam shaft may be reversed by shifting the bevel gears 123 and 124, thus reversing the rotation of the shaft 122.

Operation

Having described the construction of my improved tube frame transporting mechanism, I will now describe the operation thereof.

The guards 70 (Fig. 1) are opened and swung outward and the transporting mechanism is then placed in operation. The tube frames are inserted in slots in the links 26 as these links are intermittently moved downward past the openings in the guard 45.

The tube frames are carried around by the chains C to a position opposite the lower set of rack bars 81, by which they are removed from the chain and placed in storage on the fixed rack bars 80. The operation of the rack bars is as indicated in Figs. 8 to 12.

The tube frames are gradually advanced step by step horizontally from left to right along the lower set of rack bars and are finally inserted one at a time in the links of the chains C' which lift the links one space, at which point they are removed by the next higher set of oppositely moving rack bars 81 and are advanced to the left to another point of delivery of the chains C. This cycle of operations may be repeated as many times as is necessary to provide the necessary storage.

The process of advancing the tube frames by one of the rack bars 81 is illustrated in Figs. 8 to 12 inclusive. The normal inoperative position of the movable rack bar 81 is indicated in Fig. 10, with the gudgeons 24 of the tube frames resting in the shallow notches of the fixed rack bar 80 and with the movable rack bar 81 in lowered position corresponding to the portion 130 of the cam 101 (Fig. 17) and also in mid position horizontally, corresponding to the portion 115 of the cam 113 shown in Fig. 18. This cam 113 is then advanced, bringing the portion 116 of the cam into operative position and giving the rack bar 81 an idle stroke to the extreme right hand position indicated in Fig. 11.

The cam 101 (Fig. 17) then shifts the corresponding cam roll from the part 130 to the part 131 of the cam, thus raising the rack bar 81 to the position shown in Fig. 12. This raising movement is caused by endwise motion of the bars 93 (Fig. 5), causing rocking movement of the arms 89 and swinging the

rolls 87 from the dotted to the full line position in Fig. 5.

The feed cam 113 is then advanced to shift the corresponding cam roll from the portion 116 to the portion 114 of the cam, carrying the movable rack bar 81 from the position shown in Fig. 12 to that shown in Fig. 8. By such movement, a tube frame is removed from the chains C' and another tube frame is placed in notches in the chains C.

The cam 101 then shifts the control from the part 131 to the part 130 of the cam, lowering the rack bar 81 to the position shown in Fig. 9, after which the portion 115 of the feed cam 113 is advanced to operative position, returning the bar 81 to the position shown in Fig. 10.

It will thus appear that the movable rack bar 81 has been given an intermittent motion in a rectangular path, being moved to the right in lowered position; then raised vertically to lift the tube frames out of the shallow notches in the fixed rack bars; then moved to the left to advance a series of tube frames one space, then lowered, and finally returned to the initial position shown in Fig. 10.

This cycle of movements takes place between the intermittent advance movements of the chains C and C' and the movable rack bars are held in the intermediate position indicated in Fig. 10 during the advance movement of the chains.

It will be understood that the foregoing description of operation applies to every alternate rack bar 81 and that the intervening rack bars receive simultaneous movements which are reversed in horizontal directions, as each alternate set of rack bars is operated by a bell crank 107 and the intervening rack bars are operated by the oppositely moving bell cranks 107^a. Consequently the tube frames are removed from the chains C' and added to the chains C by each alternate pair of rack bars while the intervening bars remove tube frames from the chains C and add them to the chains C'.

In the weaving of symmetrical patterns, it is common to weave one-half of the pattern and then reverse the feed of the pattern chains to weave the other half of the pattern. My improved storage mechanism has been especially designed to permit such operation, and it is merely necessary to move one of the pawls 51 or 52 to inoperative position and the other to operative position to reverse the feed. The cams shown in Figs. 17 and 18 are so designed that they will operate equally well when rotated in either direction.

Having described the details of construction and the operation of my improved transporting mechanism, it will be seen that I have provided a very compact storage for a large number of tube frames and that this storage may be further increased by adding additional sections, so that any commercial

number of tube frames may be readily taken care of in comparatively small space. Furthermore, the chains C and C' are relatively short and the operating mechanism therefore is simple and direct.

While the description in connection with Fig. 17 and the shape of the cam set forth therein has been based on the idea that the cycle of movements of the parts controlled by cam groove 101 is divided equally into four time intervals yet if desired I may make the rising and falling parts of the cam of shorter duration so that the dwells may be increased. Also, while it is stated in connection with Fig. 18 that the bar controlled thereby may be given a dwell in intermediate position by the face 115, yet as a matter of fact the purpose of my invention will be served if a retardation instead of actual dwell is given the motion of bar 81. It is sufficient for the purpose of the present invention if the bars have their ends spaced from the chains to permit the latter to move and it will be understood that this result can be achieved either by an actual dwell or a retarding of the bars and I wish it further to be understood that where the word dwell is used herein I intended to cover a retardation.

Having thus described my invention and the advantages thereof, I do not wish to be limited to the details herein disclosed, otherwise than as set forth in the claims, but what I claim is:

1. In an Axminster loom, tube frame storage and transporting mechanism comprising superposed pairs of rack bars, means to deliver successive tube frames to one end of a pair of rack bars and to remove successive tube frames from the opposite ends of said bars, and means to produce intermittent relative movements between the members of each pair of bars, said tube frames being advanced along said bars by such intermittent relative movements.

2. In an Axminster loom, tube frame storage and transporting mechanism comprising superposed pairs of rack bars, means to deliver successive tube frames to one end of a pair of rack bars and to remove successive tube frames from the opposite ends of said bars, and means to produce intermittent relative movements between the members of each pair of bars, said tube frames being advanced along said bars by such intermittent relative movements, and alternate pairs of bars being operative to advance tube frames in opposite directions.

3. In an Axminster loom, tube frame storage and transporting mechanism comprising superposed pairs of fixed and movable rack bars, means to deliver successive tube frames to one end of a pair of bars and to remove successive tube frames from the opposite end of said bars, said tube frames being advanced along said bars by relative movements be-

tween the bars in each pair, and means to reverse the direction of operation of said transporting mechanism.

4. In an Axminster loom, tube frame storage and transporting mechanism comprising superposed pairs of fixed and movable rack bars, means to deliver successive tube frames to one end of a pair of bars and to remove successive tube frames from the opposite end of said bars, said tube frames being advanced along said bars by relative movements between the bars in each pair, alternate pairs being operative to advance tube frames in opposite directions, and manually reversible means for actuating said mechanism to feed tube frames in either direction.

5. In an Axminster loom, tube frame storage and transporting mechanism comprising superposed pairs of fixed and movable rack bars, said movable bars being notched, and means to give said movable bars a rising and falling movement and a longitudinal feeding movement.

6. In an Axminster loom, tube frame storage and transporting mechanism comprising superposed pairs of fixed and movable rack bars, said movable bars being notched, and means to give said movable bars successive upward, feeding downward, and return movements.

7. In an Axminster loom, tube frame storage and transporting mechanism comprising superposed pairs of fixed and movable rack bars, said movable bars being notched, and means to give said movable bars successive upward, feeding, downward, and return movements and to effect a dwell of said movable bars in mid-return position.

8. In an Axminster loom, tube frame storage and transporting mechanism comprising spaced fixed storage rack bars notched to receive tube frame gudgeons in closely spaced relation, and means to lift a plurality of tube frames out of said notches and to advance said tube frames simultaneously and to deposit said tube frames in successive notches.

9. In an Axminster loom, a plurality of chains to advance tube frames to operative position and to remove them from operative position, additional means to remove tube frames from said chains, to intermittently advance said tube frames through a storage device, and to restore said tube frames to said chains, and means to reverse the direction of travel of said chains and the direction of movement of said tube frames through said storage device.

10. The combination in an Axminster loom as set forth in claim 9, in which the reversing means comprises a pair of reversely operating feed pawls, and means to hold each pawl in operative or inoperative position.

11. In an Axminster loom, pairs of superposed tube frame storage racks each comprising fixed and movable rack bars, means to raise and lower said movable rack bars, and means to reciprocate said movable rack bars, the reciprocating movements alternating with the rising and falling movements of said rack bars.

12. In an Axminster loom, means to advance tube frames to and from operative position, means to place said tube frames in a storage device and to advance said frames along said storage device, cams to operate said first means, a pair of associated cams to operate said second means, means to actuate all of said cams in timed relation, and means for reversing rotation of said associated cams while said first mentioned cam continues to rotate in the initial direction.

13. In an Axminster loom, pairs of superposed tube frame storage racks each comprising fixed and movable rack-bars, transporting chains at each end of said rack bars, and means to give alternate movable rack bars simultaneous feeding movements in opposite directions, each movable rack bars removing tube frames successively from chains at one end of said bar and inserting the tube frames in the chains at the opposite end of said bar.

In testimony whereof I have hereunto affixed my signature.

ELBRIDGE R. HOLMES.
